UNITED STATES PATENT OFFICE.

SEIZO KODAMA, OF SAN FRANCISCO, CALIFORNIA, ASSIGNOR OF ONE-HALF TO HISANO KODAMA, OF SAN FRANCISCO, CALIFORNIA.

DESIGN FOR AN INCENSE BURNER.

Application filed October 10, 1921. Serial No. 506,886. Term of patent 3½ years.

To all whom it may concern:

Be it known that I, SEIZO KODAMA, a subject of the Emperor of Japan, residing at San Francisco, in the county of San Francisco and State of California, have invented a new, original, and ornamental Design for Incense Burner, of which the following is a specification, reference being had to the accompanying drawing, forming part thereof.

I claim:

The ornamental design for an incense burner, as shown.

Dated Sept. 30, 1921.

SEIZO KODAMA.
